UNITED STATES PATENT OFFICE.

JOHN C. SHERMAN, OF PORTLAND, MAINE, ASSIGNOR TO BROWN COMPANY, OF BERLIN, NEW HAMPSHIRE, A CORPORATION OF MAINE.

PAPER YARN AND PROCESS OF PRODUCING THE SAME.

Application filed November 16, 1921. Serial No. 515,484.

To all whom it may concern:

Be it known that I, JOHN C. SHERMAN, a citizen of the United States, residing at Portland, in the county of Cumberland and State of Maine, have invented new and useful Improvements in Paper Yarns and Processes of Producing the Same, of which the following is a specification.

This invention has relation to the formation from wood pulp of rovings, yarn, thread or cords.

In carrying out my invention I utilize wood pulp in the form of a web of proper width and thickness, and for this purpose I may employ the pulp strips as they are delivered from a web-forming machine, or may employ strips cut from a previously formed and dried web. In either case, the strips are wet, in the one case with water remaining therein during the web formation, and in the other case with water with which the strips are wetted. While it is obvious that strips formed of various kinds of pulp may be utilized for this purpose, it is preferable that a chemical wood pulp should be used because of the length of the cellulose fibers resulting from the mode of production thereof. In fact, in many cases, I prefer to employ wood pulp produced by the "sulphate process" so-called, in combination with other well known ingredients of a paper "furnish."

Many recognized methods exist for the forming of rovings from textile fibers, such as cotton, linen, etc., in the production of yarns or rovings, in all of which methods it is essential that the fibers utilized shall possess a length substantially greater than the length of the chemical wood fibers which are usually of the order of 3 millimeters in length or less, but no method has thus far appeared for utilizing cellulose fibers of such short length by known textile processes; and one object of the present invention is to provide means whereby these cellulose or wood fibers in combination with other well known ingredients of a paper "furnish" may now be utilized to produce yarns, rovings, etc., possessing a strength comparable to existing textile products made from longer fiber. It is impossible to accomplish this result with dry cellulose fibers, but I have found that, when such fibers possess the requisite amount of water I am able by my process herein to be described to produce strong

rovings, yarn, etc. To accomplish this result, it is essential that the sulphite or other cellulose fiber strip shall be substantially saturated, as with water, but free from all surplus fluid. It is also desirable that the fibers should be more or less hydrated in the beating operation in order to furnish the requisite amount of cementitious or gelatinous cellulose hydrate for binding the fibers together in the formation of the web and the roving. Consequently it is desirable or necessary that the stock should be beaten primarily to a "slow" state or one in which it is of a more or less slimy character due to the presence of mucilaginous hydrate. This is true whether the rovings be formed of the wet pulp as delivered from the web-forming mechanism or whether the web be initially dried after its formation and then wetted so as to have the desirable water content at the time of its formation into the yarn or thread. For the purpose of further describing but not limiting my invention, I may say that sulphate or sulphite pulp, suitably beaten and otherwise prepared for the production of a tough tissue paper, has the condition which I prefer my pulp to have for my process.

According to my process, the wet strips are subjected to a twisting operation and at the same time are wound in convolutions transversely of the length of the strip with the result that a roving is produced which is inherently round and which in cross section is spiral with one edge of the strip lying at or near the center of the spiral. I have ascertained that this may be accomplished by a simple mechanism comprising two endless belts arranged with their inner stretches confronting one another but with the belts arranged at an angle one to the other, with mechanism by which the belts are caused to travel with their inner stretches moving in the same general direction but in crossing paths. The wet strip is fed to said belts so as to be moved longitudinally of its length thereby, and, while so moving, is convoluted transversely, the result being that the strip moves in a straight line during the action of the belts thereon and is delivered in the form of a round rod or roving which is compacted and of little or no variation in thickness. Inasmuch as the belts travel unidirectionally and have no independent lateral movement, they may be

moved at relatively high speed so as to afford rapid production of the rods or rovings. The rovings thus produced may be formed into coils in the usual cans employed 5 for a like purpose in the production of textile yarns; or, being still in a moist state, they may be subjected to a twisting operation, or a plurality of strands may be twisted to form a thread or cord. The relative angularity of the confronting stretches 10 of the belt is important. Their angularity should be such that the same pair of belts may be utilized for simultaneously treating a plurality of independent closely-spaced 15 strips, for, with the increase in the degree of angularity in the belts, there is increasing danger of the strips being rolled together so as to lose their individuality. If the relative angularity exceed a certain limit, 20 there is the danger that the strips which are being rolled and convoluted will be subjected to too great transverse strain with the result that the roving is broken. For securing the best results in the primary 25 functioning of the belts which is here discussed, the angularity of the belts should not be excessive, as hereinafter explained more at length.

On the accompanying drawings, I have 30 indicated conventionally simple forms of apparatus which may be utilized in carrying out my process, but to the employment of which it will be understood the invention is not necessarily limited.

35 Referring to these drawings,—

Figure 1 represents, more or less diagrammatically, an apparatus for producing a plurality of pulp strips and for forming them into rovings.

40 Figure 2 represents a plan view of the strips of pulp being delivered from the cylinder mold.

Figure 3 represents in front elevation the 45 instrumentality by which the several pulp strips are convoluted and compacted into rovings, only one such strip being shown.

Figure 4 represents in end elevation one 50 of the belts and the supporting mechanism therefor.

55 Figure 5 represents a section on the line 5—5 of Figure 3.

Figure 6 shows more or less conventionally an apparatus which may be employed for the formation of rovings from 55 paper strips.

Figure 7 is a plan view of some of the 60 instrumentalities shown in Figure 6.

Figures 8 and 9 illustrate more or less conventionally the changes of superficial 65 forms encountered by a strip during its formation into a roving.

Referring first to Figures 1 and 2, I have indicated at 10 in conventional form the vat 70 of a web-forming machine, into which the 66 aqueous pulp stock is delivered for forma-

tion into the web upon a cylinder mold 11. This cylinder mold may be formed in any suitable or convenient way for the purpose of forming a plurality of strips. As indicated, the foraminous shell of the cylinder 75 is provided with parallel imperforate metallic circumferential strips 12 so that the web delivered by the cylinder will be in the form of separate relatively narrow strips. At 13 I have indicated conventionally a blanket or 80 felt which removes the strips from the cylinder 11 and delivers them at a point where they may be fed to the instrumentality by which they are converted into rovings. This felt is shown as carrying the strips between 85 press rolls 16, 17, for removing surplus free water therefrom. The felt passes around the usual guide and take up rolls.

Of course, it will be understood that I 90 make no claim to the mechanism for forming the pulp strips, as such devices are well known and many others may be utilized in lieu of that shown and thus described. In fact, as I have previously indicated, I may employ strips of previously formed and 95 wholly or partially dried paper in which case the strips are caused to be wetted to the desired degree by carrying them over a moistening roller, or by passing them through a bath of fluid or by subjecting 100 them to the action of spray, steam or the like, the surplus fluid being removed, if necessary, by squeeze or pressure rolls. In any event, however, as I have previously stated, the strips should be wet when being delivered to the instrumentality for forming them into rovings, so that a further hydration of the cellulose fibers may take place 105 during the operation of the rod or roving-forming instrumentalities.

Referring now to Figures 3 to 5 inclusive,—20, 21 indicate two belts having their inner stretches 22, 23 in confronting relation. These belts should be formed of or faced with such material, e. g., vulcanized rubber, that they will frictionally engage 110 the strips. Ordinarily I employ belts having a canvas or other textile body with a rubber face vulcanized thereon. Of course, if desired, the inner faces of the belts may be similarly provided with a coating of rubber that they may frictionally engage the rolls over which they run. For supporting and driving these belts, I employ the two pairs of rolls indicated at 25, 26 and 27, 28, 115 which may likewise be faced with vulcanized rubber. It is relatively immaterial what kind of frame-work is employed for the support of the rolls, except that of course provision must be made for so mounting the rolls 120 that the inner faces of the belts carried thereby may be arranged at proper angularity one to the other, so as to move in crossing paths. As shown more or less conventionally in Figures 3 and 4, these rolls are 125 130

formed on or secured to shafts 29, 30, 31, 32 which are journaled in suitable bearings in frames afforded for the purpose. It is desirable that the rolls and their shafts should 5 be capable of adjustment, and to this end the boxes, in which the shafts are journaled, are preferably adjustable relatively to the frame. Again, it is also desirable, for the purpose of varying the relative angularity 10 of the belts, that the frames themselves should be capable of angular adjustment one relatively to the other. This may likewise be accomplished by devices of any suitable character. There are two frames, each 15 shown more or less conventionally as comprising a pair of upright side standards mounted upon a suitable base. The bases for the frames are indicated at 33 and 34 respectively. The base 33 is provided with 20 the upright standards 35, 36, while from the base 34 rise the standards or uprights 37, 38. These frames may be referred to conveniently as the front and rear frames, that comprising the base 33 and the standards or 25 uprights 35, 36 being the front frame. These two frames are shown as being supported by a table 40 to which they are secured by bolts and nuts 41 and 42 with suitable washers 43 which are properly beveled. The bolts pass 30 upwardly through elongated slots formed in the base portions of the frame. As indicating a convenient means for providing for the relative angularity of the belts 20, 21, I have shown wedge-shaped shims 44, 45 35 which are interposed between the frames and the table on which they rest. These wedges may be of such angularity that the relative angularity of the belts is substantially 10° or less. Each shim, if used, is, of 40 course, properly slotted to permit the bolts 41 to pass therethrough and also to permit the longitudinal adjustment of the shims to raise or lower the frames supported thereby. As I have indicated the frames as being 45 made of wood, I have also shown angle irons 46 for increasing their rigidity. The base portion of each angle iron may be secured to the base of the associated frame by countersunk bolts 47 and nuts 48, as shown in 50 Figure 4. These devices, however, are merely conventional or incidental features of construction and relatively unimportant. The shafts 29 to 32 inclusive are journaled in suitable boxes, those for the shaft 29 being indicated at 49 and those for the shaft 26 being indicated at 50. There are similar 55 boxes for the shafts 31, 32, supported by the front frame. Each box is capable of adjustment longitudinally of its supporting upright, and to this end may be secured in place by bolts 51, 51 passed through a slot in the frame and secured after adjustment by nuts 52. In this way, each of the rolls 29 to 60 32 inclusive may be adjusted relatively to the associated roll of the pair to keep the

corresponding belt taut or for any other purpose.

As at least one roll of each pair must be driven positively and the two driven rolls must be substantially in synchronism with 70 one another, imparting uniform and substantially equal linear speeds to the two belts, I have indicated the lower rolls 26, 28 as having their shafts connected by universal coupling members 53, 54 with drive 75 shafts 55, 56, which may be driven at appropriate speeds through corresponding universal joints, not shown, from a suitable source of power. Of course, the rolls 26, 28 must be driven in opposite directions so 80 that the confronting stretches 22, 23 of the belts may move in the same general direction and at substantially the same rate of linear speed. I find it desirable to afford means for ensuring that the confronting 85 stretches of the belts will properly engage the pulp strips which are fed thereto, and, of course, any suitable devices may be employed for pressing these stretches of the belts towards one another. For this purpose, I may employ two pressure members 90 57, 58 for engaging the inner faces of the stretches 22, 23 of the belts. To reduce the friction between the belts and such pressure members, the said members may be faced with sheet metal, i. e., polished brass or other relatively noncorrodible material, as indicated at 59, 60. These members 57, 58 may be pressed towards each other by any 95 suitable yielding devices. For example, as indicated in Figure 4, each pressure member at each end may be pivotally attached to two rods 61, 62 arranged to slide relatively loosely in guides 63, afforded by lugs projecting laterally from plates 64 secured to the uprights of the frame with which said pressure member and its corresponding belt are associated. A helical spring 65 is so arranged on each rod that one end rests against 100 the rear guide 63 and the other against a cross pin 66 passed through the rod. As a result of this construction, each pressure member is supported in place and is pressed yieldingly towards the opposite member. Instead of directly engaging the rear guides 105 63, the rear ends of the helical spring 65 may engage the ends of threaded sleeves 67 which are threaded into the guides 63. By rotating these sleeves, the tension of the 110 springs may be increased or diminished as desired. Inasmuch as there is an adjusting sleeve 67 for each spring, it is apparent that, as the stretches 22, 23 of the belts pass downwardly between the pressure members, they may be subjected to increasing pressure by so adjusting the threaded sleeves 115 that the lower ends of the pressure members are pressed together with greater force than the upper ends.

To prevent downward or longitudinal dis-

placement of the pressure members 57 and 58, they are maintained in position by links 69 pivoted at one end to the boxes which support the shafts 29 and 31, and at the other ends to the rods 62.

As a result of the construction thus described, it will be seen that the belts, which operate on the pulp strips, are caused to travel in the same general direction downwardly as indicated by the arrows in Figure 5, and that, during their downward movement, they travel in crossing paths. Consequently, when a pulp or paper strip having the proper moisture content is so delivered as to be gripped by the belts, it is carried downwardly with them and at the same time is convoluted laterally, twisted and compacted into a roving which is practically round in cross section, with one edge of the strip forming the center of the roving. Since the cellulose fibers have been more or less hydrated and are in a wet state in addition, they are, by the pressure of the belts, cemented together and more or less interfelted. While the belts, because of their rubber facing, more or less positively grip the strip and the roving into which it is formed, nevertheless the belts are pressed yieldingly towards each other so as not to tear the fibers apart or destroy their initially interfelted relation. It is obvious, however, that in a yarn or roving it is desirable that the fibers shall lie along a longitudinal direction or axis of the roving. This result can be best accomplished with my invention if the fibers are delivered to the belts from a pulp-forming machine adapted to deliver the fibers along the axial direction of the strip of pulp. Thus I may use a suitably designed cylinder mold for initially forming the web. Furthermore, to secure substantially this longitudinal lie of the fibers within the roving, it is important that the strip of wet pulp or wetted paper, in passing between the belts, shall be moved axially forward over a much greater distance than the lateral displacement produced by the angularity of the two belts relatively one to the other. As above stated, an angularity of 10° accomplishes this desirable result in the particular instrumentality as here described and illustrated. If the angularity be excessive, the wet strip is so tightly twisted upon itself in such way that the fibers no longer lie axially, with the result that the roving will not be strong but will tend to break before emerging from the belts. It is evident that the number of twists, which may be imparted to the roving between the point where the strip enters between and the roving emerges from the belts, will depend upon two factors, to wit: the relatively angularity of the belts and the length of the contacting inner stretches of the belts. It is obvious that two belts, po-

sitioned as herein described with a certain angularity, will tend to be displaced laterally upon their individual rollers. Therefore one belt will tend to pile up upon the supporting frame-work at one side of the device, and the other belt to pile up similarly upon the opposite frame of its supporting members. To overcome this tendency, it is necessary only to introduce between the belts a plurality of strips of wetted paper or wet pulp, whereupon these wet strips counteract the tendency of the belts to undergo lateral displacement, with the result that the belts may "float" in mid position substantially as if carried upon crowned pulleys. If, however, the belts are not doing work upon the rovings throughout their entire working faces, or if the adjustment of the working parts be faulty, the piling up referred to will occur and must be counteracted by increasing the distance between the rollers which support a given belt at that side of the belt which tends to pile up.

Preferably, as each strip passes between the belts and is formed into a roving, it is subjected to increasing pressure, this being effected by adjustment of the springs 65 which bear against the pressure members; that is, by decreasing the pressure of the upper springs and increasing the pressure of the lower springs upon the pressure members. Such adjustment may not, in any given instance, be imperative, however, because if the contacting stretches of the belts be substantially parallel it is obvious that the strip as it becomes a roving during its transit between the belts will acquire a continually increasing diameter until it is completely spiralled up at some point of its progress between the belts and will thus encounter an increasing pressure from the belts during that portion of its transit between its entrance as a flat strip between the belts and its complete rounding up.

As the rovings emerge from between the belts, any wide variation from the normal moisture content of the said rovings may cause the rovings to stick to one or the other of the two belts. To counteract this tendency, the roving is permitted to fall by its own weight through a substantial distance before it is coiled up in a can or is wound upon a bobbin or a spool. This overcomes any tendency of the rovings to wind up with the belts. Obviously I may further counteract the possible tendency of the rovings to stick to the belts by providing doctors or scrapers so located as to deflect any rovings, which may stick to the belts upon their upwardly moving portions, and cause these to drop down again into their proper position, but since such doctors and equivalent devices are well established in the pulp and paper making art they have not been shown.

It will be noted that the strip is led to the

belts adjacent to their engagement with their tank 104, into which dips a moistening roll 105 over which the strips pass to a guide roll 107 prior to their delivery to the crossed belts by which they are formed into rods or 70 rovings. Any suitable appliances may be utilized for causing one of the pressure rolls, the moistening roll and the guide roll 107 to be driven at the same peripheral speed and at the surface speed of the forming belts, particularly where fine strips of unusual delicacy are employed in making fine 75 roving. Where strips of stronger quality are utilized, I prefer to let the strips themselves rotate the moistening roller by their own frictional contact, for the purpose of 80 subjecting them to a slight drawing or straining effect, which, in some cases, assists in conserving or increasing the desirable formation or arrangement of fibers lengthwise of the strips. I have illustrated 85 conventionally an endless belt 108 which is engaged with the end of the roll 103 for rotating the same and which is driven by one of the forming belts, being passed between the belts near their outer edges so as to move 90 at a linear speed equal to that of the belts. This endless belt 108 is illustrated as being passed around a take-up roll 109. Of course, it could, if desired, be engaged with 95 rolls 105 and 107 so as to drive them positively.

In Figure 1, I have indicated a strip at *a* 15 and the roving formed thereby at *b*. The roving *b* is shown as passing downwardly into a stationary roving can indicated at 70, it being unnecessary to rotate the can as the roving emerges from the belts with an inherent 20 tendency to coil if it is dropped free. In Figure 1, the roving can 70 is indicated conventionally as being at the right end of the apparatus for the purpose of clearness. In place of the roving can, as shown in Figure 25, the roving may pass to a suitable spooling mechanism as indicated at 75 in Figure 6. It is quite evident that, instead of preserving the identity of the individual rovings as by coiling them in individual cans or winding them on individual spools, the entire number of strips emerging from 30 the belts may be divided into groups, the rovings of one group may be brought together and the several groups delivered to a 35 second instrumentality comprising crossed belts (similar to those at 20 and 21), whereby each group of rovings is formed into a thread having an equal number of strands. While for many purposes it is desirable to 40 treat the initially wet pulp delivered from the forming cylinder, yet, for other purposes, it is desirable to treat strips of previously formed and dried paper. In Figures 6 and 7, I have shown conventionally 45 an apparatus in which such latter strips of paper may be conditioned for treatment.

In using paper strips, I prefer to have them delivered in the form of separate rolls 100 in which the cores are hollow so that they may be slipped upon a supporting shaft or 50 bar 101 and so that each roll may revolve independently of the adjacent rolls. The free ends of the strips drawn from the rolls are passed between feed rolls indicated at 55 102, 103, one at least of which is driven so that the strips may all be fed at the same linear feed. It is necessary that the strips should be supplied with the proper degree 60 of moisture for their subsequent formation into rods or rovings. This might well be accomplished by passing the strips through an aqueous bath, or they may be passed over a roll which dips into the bath as shown upon the drawings. The moistening liquid 65 is illustrated as being contained in a vat or

Care should be taken, in any event, to prevent an excess of moisture in the strips, whether they be wetted as when utilizing already formed and dried strips, or in utilizing strips as delivered from the cylinder mold. On the other hand, it is desirable that there should not be a deficiency of moisture, as in such case the strips cannot be properly formed into rods or rovings. 100 Where previously formed and dried strips are employed, I prefer in ordinary cases to use water as the moistening agent, but it is evident, of course, that I may substitute 105 a sizing compound including a hydrating 110 agent.

As a result of experience and much experimental work, I have come to the conclusion that, when the pulp or paper strips, having a sufficient free-water content, are subjected to the action of the rod-forming belts, the cellulose fibers are hydrated to a considerable extent, and that the mucilaginous hydrate serves as a cementing or binding agent to bind the fibers together 115 in the completed rod or roving. This is due, I believe, to the noticeable operations which occur during the treatment of the strips with the belts by which they are convoluted transversely.

First, the wet or wetted strip enters between the belts where it is first pressed between them with a slightly obliquely applied pressure, this obliquity of direction being due to the relative angularity of the 120 125 130

belts. This obliquity of pressure lines tends slightly to abrade one face of the now flat and compressed strip in, for example, a right-handed obliquity, by reason of the 5 action of the belt in contact with that face, and slightly to abrade the opposite face of the same strip in, for example, a left-hand obliquity, by reason of the action of the other belt acting on said opposite face. 10 These obliquely abrading functions persist for an appreciable interval during which the wet and compressed strip is, as it were, subjected to two opposing forces, one imparted by the pressing belts which tends to maintain 15 the strip flat and the other imparted by the obliquely shearing tendency of the belts to convolute the strips. During the incidence of these two opposing forces, considerable abrasion of the surfaces of the 20 strips occurs.

Second, the partially loosened and abraded masses of pulp within the structure of the strip now pass on under the dominating obliquely twisting-up influence of the 25 belts. The strip is no longer flat, and it is ragged at its edges and rough upon its faces, and in this condition it is suited to be further convoluted transversely with a far more intimate bonding and blending of 30 the fibers of adjacent convolutions than would be possible if the strip were smooth. These operations of the belts upon the fibers in the presence of the contained moisture effect a hydration of the fibers so that 35 the strip emerges from between the belts with a remarkably increased tensile strength. Its strength is sufficient to permit the operator to carry its free end by hand to spindles or other receiving devices far 40 distant from the belts. A tougher and more durable roving is formed by permitting it to dry in an unconstrained condition, as when it is coiled in a roving can, as by permitting the roving to drop from the 45 belts into a suitable can. If, on the other hand, the roving be spun or spooled immediately after emerging from the belts, it obviously dries out under a condition of strain; but, even so, although it is not as 50 strong as a roving dried without constraint, nevertheless it is sufficiently strong for a great variety of purposes. In some cases, I prefer to have the rovings partially dried 55 after their emergence from the belts, if a soft yarn is required. If it is desired to twist a roving into a tightly-twisted single-ply yarn, such tight twisting is more readily accomplished while the roving still contains more or less free water. Rovings, such 60 as furnished by the process and apparatus herein described, whether formed of pulp strips or moistened paper, may be conditioned and finished according to well known textile processes, they may be boiled in hot 65 dyes without injury, or treated in accord-

ance with the usual conditioning, bleaching or finishing processes for the formation of textile yarns or rovings or woven or knitted fabrics.

In an apparatus for forming rovings such 70 as herein described it is obvious that the relative obliquity of the belts depends in a measure upon their length and their width, these factors themselves also being governed to some extent by the number of the strips 75 which are being treated. Of course the "working area" of the belts, i. e., those portions of the faces of the belts between which the strips and the resulting rods or rovings are being treated, is relatively small as compared with the length of the belts. The relative obliquity of the belts in the same general direction must not be so great that the confronting face of one may pass entirely beyond the lateral edges of the other 80 within the limits of the working area, as this might cause all of the rovings to be massed together.

The particular device here illustrated is designed and built to accommodate a plurality of separate but parallel strips occupying a lateral distance of approximately 8 inches, and in this device a relative obliquity or angularity of the belts amounting to approximately 10° suffices to maintain the strips and rovings in effective contact with the belts throughout a longitudinal distance of about four inches. It is obvious that if the device had its linear dimensions ten times as great, the strips and rovings will 90 remain in effective contact with the contacting belt faces or stretches over a longitudinal distance ten times as great and would thus receive ten times as much rolling and rounding action and the angularity of the belts is correspondingly reduced. In the case of the larger machine, this is effected by reducing the relative angularity of the belts from ten degrees to one degree. Obviously, however, the frictional character of 95 the contacting belt stretches must be adapted to sustain the requisite frictional engagement between the strip and the stretches at any angle chosen for the operation of the machine, and this adaptation is secured by the right selection of surfacing material in the construction of the belts. In general, as the angularity of the belts is reduced their surfaces must possess an increasing frictional action which to some extent is afforded by the appropriate adjustment of the mechanism to determine the pressure between 100 said belts and to some extent by the right selection of belt-making materials. Thus if the angle be a small acute angle, canvas belts will function suitably. If the angle be made greater, smooth surfaced rubber surfaced belts may be employed.

Furthermore, though the fact is obvious, it may be stated that the character of the 105

- rovings,—its relative softness or hardness, and to some extent its tensile strength, is conditioned by the speed with which it is rolled up and rounded between the belts. 5 But the speed of the belts is conditioned on the speed of the strip or web-forming machine employed to supply the said strip or web, and it must for commercial reasons be as great as possible. If the lineal or longitudinal motion of the strips and rovings be relatively fast it is desirable to impart to them the rounding up effect in a gentle rather than abrupt manner. Therefore for a fast running machine I prefer to employ 10 relatively wide belts and to set them at a relative angle correspondingly small, retaining the rovings between said belts for a correspondingly longer longitudinal distance. 15 While, during the transit of the wet strips of pulp between the belts, more or less water is expressed in amount sufficient to leave a wet track on the belts, yet there apparently is little diminution of the water content in the rods or rovings as compared 20 with that of the strips, since the water thus expressed is taken up by the oncoming lengths of the strips as they are engaged by the belts. It is apparent, of course, that the rods or rovings contain free water when 25 emerging from the belts, although undoubtedly a portion of the initial free water content is consumed in the hydration of the fibers, and this I think accounts in part for the absence of accumulated water dripping 30 from the belts when the machine is in operation. The wet rods or rovings might be said to have the fibers "autogenously cemented" by the hydrated cellulose which results from the action of the belts on the 35 strips.
- Figures 8 and 9 of the drawings are intended to show, more or less conventionally of course, the formation of a wetted tissue paper strip into a rod or roving. The strip, as indicated in Figure 8, has its face *x* abraded or rubbed, and the side edge *y* is rolled over to form the center of the resulting rod, the remainder of the strip being coiled transversely around it. At the same 40 time the rod is also twisted relatively loosely, as best shown in Figure 9. The resulting rod or roving appears to be a homogeneous bundle or intimately cemented series of fibers, incapable of being uncoiled, and possessing a strength not greatly inferior to that of a cotton roving of the same size. The mucilaginous cellulose hydrate, or hydrated portions of the fibers, bind the fibers together in such manner that the yarn or 45 rod may be boiled without affecting its integrity or strength.
- What I claim is:
1. A roving formed of cellulose fibers, consisting of a fibrous strip initially coiled transversely about one of its longitudinal edges, and having the fibers of its coils united together. 65
  2. Roving formed of cellulose fibers and consisting of a fibrous strip, whose face is initially abraded, coiled transversely about one of its edges and having the fibers of the coils interfelted and cemented by the cellulose mucilage of the fibers. 70
  3. Roving formed of cellulose fibers and consisting of a round compacted fibrous strip coiled transversely about a longitudinal portion thereof as the center, the fibers of the coils being felted and being cemented together by the hydrated portions of such fibers. 75
  4. Roving formed of cellulose fibers and consisting of a fibrous strip coiled transversely about one of its edges and having the fibers of the coil interfelted and cemented by the cellulose mucilage of the fibers, the whole being loosely twisted. 80
  5. A method of making a roving which comprises progressively subjecting a continuous flat wet strip of cellulose fibers to obliquely applied frictional pressure exerted in opposite directions laterally of the strip and in the same direction longitudinally thereof, whereby the strip is coiled transversely into cylindrical form and fed 85 forwardly. 90
  6. A method of making a roving which comprises passing a continuous flat wet strip of cellulose fibers between a pair of crossing obliquely arranged continuous frictional members which traverse unidirectionally in paths oblique to and having a component of motion in the same direction longitudinally of the strip and a component of motion laterally of the strip in opposite directions whereby said strip is fed forwardly and converted into substantially cylindrical form. 95
  7. The method of producing a roving which comprises progressively pressing and abrading the opposite faces of a flat wet 100 strip of fibrous material and simultaneously feeding the strip forwardly and coiling it laterally about one edge while subjecting it to pressure.
  8. A method of producing a roving which comprises feeding a flat wet strip of fibrous material, pressing and abrading the opposite faces of said strip, and coiling said strip laterally about one edge while subjecting it to pressure, thereby producing a 110 compacted substantially cylindrical rod or roving. 120
  9. A method of producing from cellulose fibers a roving, which comprises feeding a flat wet strip of such fibrous material, and subjecting the opposite faces of said strip to obliquely moving friction members, thereby pressing, roughening the faces of, and 125

coiling said strip transversely and compacting said strip into substantially cylindrical form.

10. A method of making a roving comprising feeding a flat strip of wet paper pulp longitudinally of its length, and, by the obliquely applied pressure of friction members, hydrating the cellulose fibers with the water contained in the strip, transversely coiling said strip about one edge thereof, compacting the resulting rod or roving and cementing the fibers thereof by the cellulose hydrate.

11. Mechanism for producing a roving from cellulose fibers which comprises a pair of crossed obliquely disposed endless belts having confronting faces moving in the same general direction to feed a wet strip of such material therebetween, and having a component of motion laterally of the path of motion of said strip in opposite directions to coil said strip laterally, and means for driving said belts.

12. Mechanism for producing a roving from cellulose fibers which comprises a pair of crossed obliquely disposed endless belts having confronting faces moving in the same general direction to feed a wet strip of such material therebetween, and having a component of motion laterally of the path of motion of said strip in opposite directions to coil said strip laterally, means for driving said belts, and pressure members for pressing the confronting stretches of the belts together.

13. Mechanism for producing a roving from cellulose fibers which comprises a pair of crossed obliquely disposed endless belts having confronting faces moving in the same general direction to feed a wet strip

of such material therebetween, and having a component of motion laterally of the path of motion of said strip in opposite directions to coil said strip laterally, means for driving said belts, pressure members for pressing the confronting stretches of the belts together, and means for varying the pressure of said member upon the said confronting stretches.

14. Mechanism for producing a roving from cellulose fibers which comprises a pair of obliquely disposed endless belts, a pair of rolls over which each of said belts is carried and arranged to produce confronting stretches in said belts, the corresponding rolls of each belt being substantially opposite to each other whereby the belts adjacent to said rolls form opposite sides of a substantially hopper-like structure, and means for driving said belts so that the confronting stretches move in substantially the same longitudinal direction, whereby a strip of cellulose fibers directed into said hopper-like structure will be fed between said confronting stretches.

15. Mechanism for producing a roving from cellulose fibers which comprises a pair of obliquely disposed endless belts, a pair of rolls for supporting each belt and arranged to produce confronting stretches in said belts, and means for driving said belts in a manner to cause said confronting stretches to move in the same general direction, the rolls at the initial ends of said confronting stretches being substantially opposite each other to receive and direct a strip of the material therebetween.

In testimony whereof I have affixed my signature.

JOHN C. SHERMAN.
